O. LOGAN

FOUNTAIN PEN

Filed April 4, 1922

FIG. 1.

FIG. 2.

FIG. 3.

FIG. 4.

FIG. 5.

INVENTOR:

Orwell Logan

By Crane & Maynard

ATTORNEYS:

UNITED STATES PATENT OFFICE.

ORWELL LOGAN, OF EVERETT, MASSACHUSETTS.

FOUNTAIN PEN.

Application filed April 4, 1922. Serial No. 549,650.

To all whom it may concern:

Be it known that I, ORWELL LOGAN, of Everett, in the county of Middlesex and State of Massachusetts, a citizen of the 5 United States, have invented a new and useful Improvement in Fountain Pens, of which the following is a full, clear, and exact description, reference being had to the accompanying drawings, forming a part of 10 this specification, in explaining its nature.

The invention relates to an improvement in fountain pens and has for its object a means or device for controlling the flow of ink to the pen point or nib.

15 The invention is illustrated in the light of a fountain pen having an ink-containing reservoir consisting of a collapsible sac to which type of fountain pen the invention is especially applicable, and in which—

20 Figure 1 is a view of the fountain pen partly in longitudinal section and partly in side elevation.

Fig. 2 shows an enlargement of the sectional part of the fountain pen shown in 25 Fig. 1.

Fig. 3 is an end elevation of the controller plug to which special reference will later be made.

Fig. 4 is a longitudinal section of a slightly 30 modified construction, and

Fig. 5 is an end elevation of the controller plug shown in Fig. 4.

Referring to the drawings:—

1 represents the body or barrel of the 35 fountain pen. 2 is the flexible ink-containing sac or reservoir within the body. The open end 3 of the sac is attached to the tubular end 4 of a section or piece 5 fitting within the end of the body or barrel. The section 40 5 preferably has a snug sliding fit within the end of the barrel to permit of the ready insertion of the sac, and is cemented to the barrel. 6 is the pen-carrying section. This section is applied to the end of the barrel by an end 7 thereof fitting within the section 5 and being threaded thereto, thereby permitting of the easy removal of the section 5. 8 is the pen point or nib and 45 9 the feed bar. The feed bar is provided with a channel 10 through which ink is directed onto the pen point, the ink communicating with the channel by passage out of the reservoir through the interior of the sections 5 and 6 to the rear end of the feed 50 bar and thence into the channel. Communication from out of the reservoir to the chan-

nel 8 of the feed bar and pen point is controlled by a valvular plug 11. This plug lies back of the feed bar and is adjustable within the pen-carrying section 6 by means 60 of a threaded connection 12 between the section and plug. The plug is provided with a channel 13 through it. The plug is adjustable in relation to the rear end of the feed bar which forms as it were a valve seat 65 for the plug. When the plug is positioned by its adjustment to have contact with the rear end of the feed bar all communication is broken between the reservoir, the channel 13 of the plug and the channel 8 of the feed 70 bar and pen point. Upon the adjustment of the plug away from the end of the feed bar any amount of space 14 determinate upon such adjustment may separate the plug from the end of the feed bar, such space 75 affording connection between the channel 13 of the plug and the channel 8 of the feed bar, the flow of ink being thereby determined inasmuch as the flow will depend upon the adjusted position of the plug and 80 the extent of space separating the plug from the end of the feed bar. For the purpose of better obtaining a graduated amount of opening between the plug and the feed bar or an entire closure of such opening, if it 85 be desired, the rear end of the feed bar is preferably provided with a conical extension 15 and the plug is provided with a corresponding recess 16 by which it fits over the extension. The plug is adjusted from its 90 inner end or face 17 which is provided with a slot 18 for receiving any suitable tool for turning the plug. The adjustment of the plug may be obtained upon the removal of the pen-carrying section 6 from the barrel 95 when the plug becomes easily accessible for adjustment.

In Fig. 4 a slightly modified construction is shown. In the first place there is provided a pen-carrying section 20 having a sliding fit within the end of the barrel to which it may be cemented and provided with a tubular end 21 to which the sac is secured. The pen-carrying section is provided with a valvular plug 22 adjustable within it the same as the plug 11 in the construction first described and functioning in precisely the same manner. The plug 22, however, is provided with an extension or thumbpiece 23 on the inner end thereof which extends 100 into the chamber of the sac and which permits of the plug being turned on the re-

moval of the pen-carrying section and sac with it on the flexing of the sac. While this latter construction has certain advantages, the construction first described is perhaps 5 preferable inasmuch as access may be had to the plug for adjusting it without the removal of the sac or the undoing of any cemented joint.

Having thus fully described my invention, 10 I claim and desire to secure by Letters Patent of the United States:—

1. In a fountain pen, the combination comprising the body of the pen, a pen-carrying section having normally a fixed 15 relation to the body of the pen though removable therefrom, a pen point, a channelled feed bar, and a valvular plug arranged back of said feed bar and adjustable on said pen-carrying section whereby it may 20 cooperate with said feed bar when adjusted to control communication to the pen point out of the body of the pen.

2. In a fountain pen, the combination comprising the body of the pen, a pen-carrying section having normally a fixed relation to the body of the pen though removable therefrom, a pen point, a channelled feed bar, a valvular plug arranged 25 back of said feed bar and adjustable on said pen-carrying section whereby it may cooperate with said feed bar when adjusted to control communication to the pen point out of the body of the pen, and means whereby the adjustment of said plug may 30 be obtained on the removal of said pen-carrying section from the body of the pen.

3. In a fountain pen, the combination comprising the body of the pen, a pen-carrying section having normally a fixed 40 relation to the body of the pen though removable therefrom, a pen point, a channelled feed bar, a valvular plug arranged back of said feed bar and adjustable on said pen-carrying section to leave a determinate 45 space between it and the feed bar or close said space by contact with the feed bar.

4. In a fountain pen, the combination comprising the body of the pen, a pen-carrying section having normally a fixed relation to the body of the pen though removable therefrom, a pen point, a channelled feed bar, a valvular plug adjustable 50 on said pen-carrying section back of said feed bar to leave a determinate space between the forward end thereof and the rear end of the feed bar or close said space by contact with the rear end of the feed bar, and means whereby the adjustment of said plug may be obtained on the removal of said pen-carrying section.

5. In a fountain pen, the combination comprising the body of the pen, a pen-carrying section having a fixed relation to 65 the body of the pen though removable there-

from, a pen point, a channelled feed bar having a projection from the rear end thereof forming a seat, and a valvular plug adjustable on said pen-carrying section back of the feed bar and recessed at the forward 70 end thereof to engage said seat or occupy a determinate spaced position with relation thereto upon the adjustment of said plug.

6. In a fountain pen, the combination comprising the body of the pen, an ink-carrying sac within said body, a section to which the forward end of said sac is secured, a pen-carrying section having a fixed relation to the body of the pen though removable therefrom, a pen point, a channelled feed bar, and a plug located between the mouth of said sac and the rear end of said feed bar and adjustable on said pen-carrying section whereby it may be moved to engage said feed bar or moved to leave 85 a determinate space between it and the feed bar.

7. In a fountain pen, the combination comprising the body of the pen, an ink-carrying sac, a removable section within the body to which said sac is secured, a pen-carrying section having a fixed relation to the body of the pen though removable therefrom, a pen point, a channelled feed bar, a plug adjustable on said pen-carrying section 95 and movable to engage the rear end of said feed bar or occupy when adjusted a determinate spaced position with relation thereto, and means whereby the adjustment of said plug may be obtained upon removal of 100 the pen-carrying section.

8. In a fountain pen, the combination comprising the body of the pen, a removable flexible sac within said body, a pen-carrying section, a channelled feed bar, a pen point, an adjustable plug arranged back of said feed bar and co-operating with said feed bar to control communication between the sac and the pen point, said plug being provided with an extension into said sac by 110 which the plug may be manually adjusted upon flexing the walls of said sac.

9. In a fountain pen, the combination comprising the body of the pen, a flexible sac inside the body, a section connected to 115 the body and to which the sac is secured, a pen-carrying section removably secured to said first-named section to occupy normally a fixed relation to the body of the pen, a pen point, a channelled feed bar, a channelled plug arranged within said pen-carrying section and having threaded connection therewith whereby it may be adjustable endwise thereon and thereby be moved to co-operate with the feed bar for controlling 120 communication between the sac and the pen point, and means whereby said plug may be adjusted upon the removal of the pen-carrying section.

ORWELL LOGAN.
